United States Patent Office

Des. 183,734

Patented Oct. 21, 1958

183,734

CLOTHES HAMPER OR SIMILAR ARTICLE

Harold Gleitsman, New Rochelle, and Carl Fuerst, Bronx, N. Y., assignors to Gleitsman's, Inc., Long Island City, N. Y., a corporation of New York

Application July 22, 1957, Serial No. 47,025

Term of patent 14 years

(Cl. D58—4)

FIG. 1

FIG. 2

FIG. 3

Fig. 1 is a front elevational view of a clothes hamper, showing our new design;

Fig. 2 is a side elevational view thereof; and

Fig. 3 is a top plan view thereof.

The side not shown is the same as the side shown. The rear is plain.

We claim:

The ornamental design for a clothes hamper or similar article, substantially as shown and described.
